WILLIAM DAMEREL, OF BROOKLYN, NEW YORK.

Letters Patent No. 71,587, dated December 3, 1867.

IMPROVEMENT IN BUILDINGS.

The Schedule referred to in these Letters Patent and making part of the same.

TO ALL WHOM IT MAY CONCERN:

Be it known that I, WILLIAM DAMEREL, of Brooklyn, in the county of Kings, and in the State of New York, have invented a new and useful Improvement in Buildings; and I do hereby declare that the following is a full, clear, and exact description thereof, which will enable those skilled in the art to make and use the same, reference being had to the accompanying drawing, forming part of this specification, in which drawing—

Figure 1 is a front view of a portion of a wall made according to my invention.

Figure 2 is a side view thereof.

Figures 3 and 4 are modifications of my invention.

Similar letters indicate corresponding parts.

This invention relates to the construction of face-walls for buildings, and is especially valuable where it is desired to give a finished appearance to the fronts of stone, brick, or wooden buildings.

The invention consists in a novel construction and application of a finished face-wall or surface to an ordinary outer wall of buildings, whereby the latter is improved and beautified in appearance, and also protected from injury by fire or otherwise.

In this example, I have shown my improvement applied to a wall, *a*, composed of wood. The letters *b* designate blocks of stone of uniform thickness, except the lower block, which, if desired, is made thicker than the others, to form a base. The rear sides of the blocks have plane surfaces, to enable them to set close against the wall *a*. The said wall *a*, whether it be of wood, stone, or other material, is made with an even exterior surface, against which I place the facing-blocks *b*, one upon the other, as shown in the drawing, locking the upper one to the lower one, by means of articulating joints, as hereinafter explained. The upper front edge of each block, *b*, is sawn or cut out, so as to form a joint, which is articulated, and locked with a joint made in reverse, on the lower back edge of each block, above the base-block. The joint on the upper edges of the blocks consists of a flange, *c*, whose rear surface is a continuation, in a straight line, of the back of the block. The exterior or face of said flange *c* is parallel with its rear surface, but its top, which is the top of the joint, is sawn or cut to a bevel, that inclines downwards, and forms an acute angle with the face of the flange.

The bottom, *f*, of the joint is either inclined downwards, like the top of flange *c*, as is shown in the lower joint 1 of the series, fig. 2, or it is curved, as is shown at the joint marked 2, or it is made square, as is shown at 3. The reverse joint on the lower back edge of each block is the counterpart of the joint made on the upper part of the block below it, and consists of a flange, *d*, whose exterior and interior faces are vertical and parallel, and equal in length to the upper flange *c* of the block on which it is to be placed. The lower joint of each block is the counterpart of the upper joint of the block below, so that the blocks are made to interlock, as shown in the drawing.

Each block is fastened to the wall *a* by bolts or other proper fastenings. In this example, I fasten the blocks by means of screws, which go through the flange *c* of each block and enter the wooden wall *a*, their heads being countersunk in the flange. When I apply my improvement to a stone or brick wall, I use a bolt or bolts, as shown in red outline in fig. 2, whose heads are likewise countersunk in the flange, and extend the same through the main wall in the interspaces between adjacent stones or bricks, and fasten the bolts by nuts of sufficient width to span the interspaces through which the bolts pass. By laying the face-wall in this manner, I secure each face-block, and hold it in place, by fastening its top directly to the main wall, and interlocking its bottom to the top of the block next below. The part of the joint which is exposed is pointed up by the mason, and, in practice, I cut off the sharp angle on the outer exposed edge, to give a better opportunity for the workman in pointing up.

When, from the character of the material used in the face-wall, or from other causes, there is danger of injury from the lodgment of rain or moisture along the outer part of the joint, I modify the joint, by making that part square, as shown on the upper block in fig. 2, and also in the modification, fig. 3.

In fig. 2 I have also shown another mode of making the exposed outer part of the joint, the same being designated by the numeral 2, the object being to protect the joint from the weather, and to exclude rain and moisture, and thereby avoid injury to the stone from frost, which is effected by rounding that portion of the joint, the lower side of the upper block being concave, and the upper side of the lower block convex. This

construction of the outer part of the joint effectually excludes water and moisture, the overlap of the upper block forming a perfect water-shed, and it also aids the bevelled joint on the top of flange *c* in locking the blocks to each other.

When it is only necessary that one portion of the several joints articulate with each other, for the purpose of holding the blocks securely together, the portion that is not bevelled can be made straight, as is shown in the modifications, figs. 3 and 4, the outer or inner joints being made bevelled or square, as desired, but I prefer to have the outer joint square or inclined outwards, or else overlapped, as at 2 in fig. 2, so as to prevent the entrance of rain.

The flange *c*, which is the portion of my face-wall that is directly fastened to the main or inner wall, is hidden from view and protected from the weather by the overlapping flange *d* of each successive block or slab, and, consequently, each outer flange *d* forms a lap-joint to the part *c* of the several slabs.

I do not confine myself to the forms, herein shown, of the outer joints of the wall, as they may be varied in many ways for the purpose of shedding rain and preventing the retention of moisture.

Among other advantages of my invention are the following: It enables me to cover the main wall with a handsome ornamental facing of durable material, such as slate, marble, or other stone, at a small cost and with little labor. It enables me, also, to cover and protect wooden walls, or the surfaces of framed or wooden buildings, with a handsome stone outer wall, which will present the appearance of a solid stone wall, and will protect the building from taking fire from without.

The blocks *b* are one and a half inch in thickness, more or less, and are made of any good stone or mineral material that has the requisite durability. The lower or base-stone *b* is locked at bottom by letting it in a groove in the sill-course, or, in the case of a wooden building in a groove in the coping of the foundation, so as to prevent displacement. The vertical edges of the facing-blocks *b*, at the openings for doors and windows, are dressed by casings of the same material, or of stone of different colors, or of marble, the ends of said casings being let into the sills and lintels of the buildings, so that they are held secure without other fastenings.

My improvement enables me to use very thin blocks or slabs for facing walls and buildings, and the setting of the stone is greatly facilitated, and the common danger of the sogging or winding of the wall at the joints, where thin slabs are used, is obviated or diminished.

What I claim as new, and desire to secure by Letters Patent, is—

1. The combination, in a face-wall, of a lap-joint, with bevelled articulations, substantially as described.
2. In a face-wall, the combination, with the bevelled joint at the top of flange *c*, of the rounded joint on the outer side of the wall, substantially as shown.
3. The combination, with the bevelled joint on the top of flange *c*, of the square outer joint, shown on the upper block in fig. 2, substantially as described.

This specification signed by me, this twenty-sixth day of August, 1867.

WILLIAM DAMEREL.
